UNITED STATES PATENT OFFICE.

JOSEPH BENJAMIN ALLEN, OF WOOLLAHRA, NEAR SYDNEY, NEW SOUTH WALES,
AUSTRALIA, ASSIGNOR OF ONE-HALF TO HERBERT JAMES PRESTON, OF SYDNEY,
NEW SOUTH WALES, AUSTRALIA.

SUPPORTING AND HOLDING BRACKET FOR CURTAIN RODS AND THE LIKE.

Application filed September 22, 1920. Serial No. 411,925.

To all whom it may concern:

Be it known that JOSEPH BENJAMIN ALLEN, a subject of the King of Great Britain and Ireland, residing at Woollahra, near 5 Sydney, in the State of New South Wales, Commonwealth of Australia, has invented certain new and useful Improvements in Supporting and Holding Brackets for Curtain Rods and the like, of which the following is 10 a specification.

This invention relates to devices for removably supporting and holding the ends of curtain rods, stair carpet rods and the like, and the objects of the invention are:—

15 1st. To provide a simple device which can be readily stamped out of sheet metal and assembled without additional fitting.

2nd. A device for the purpose, having no springs.

20 3rd. A device by means of which the rod is retained in position by a positive lock.

4th. A device which is simple, light, and pleasing in appearance and which can be readily manipulated.

25 The invention comprises two essential parts:

1st. A right-angled bracket or anchoring piece adapted to be secured in a fixed position by screws or the like, and having one or 30 more projecting members on one of which are vertically disposed hinge pins or trunnions and a catch or locking device.

2nd. A movable covering and locking piece supported by and having vertical and 35 swinging or partial revolving movement on and about the hinge pins on the said bracket or anchoring piece, and a complementary locking or catch device.

The functions of the bracket or anchoring 40 piece are (a) to provide a support for the end of the rod and for the movable covering and locking piece; (b) to form an abutment to prevent longitudinal movement of the rod when in position and (c) to provide a catch 45 or locking device for movable covering and locking piece.

The functions of the movable covering and locking piece are: (a) when in the open position to permit the rod to be placed in position on the bracket, or to be removed therefrom, and (b) in the closed position to positively lock the rod on the bracket.

The hinged covering and locking piece requires two movements to operate it in either

direction, in the manner following:—To 55 move it from the locked position to the open position requires 1st a vertical lift to release it from engagement with the catch or locking device on the supporting bracket and 2nd while in the raised position a swinging or partial rotating movement about the hinge pins or trunnions which causes it to move out of the path of the rod end. To close and lock the covering piece after the rod is in position requires a similar swinging movement in the opposite direction which brings it into the closed position and into alignment with the catch or locking device on the supporting bracket, when it can be dropped, lowered or pressed into engagement therewith.

But in order that the invention may be clearly understood reference will now be made to the drawings which accompany and form part of this complete specification and 75 in which:—

Figures 1 to 9 inclusive illustrate the invention in its simplest form, and Figures 10 to 19 show various slight modifications in design illustrating the application of the 80 invention to suit different positions and requirements.

Figure 1 is a perspective view of a left hand rod support in the open or free position.

Figure 2 is a similar view of a right hand support.

Figure 3 is a similar view to Figure 1 showing the covering piece lifted and swung into the closed but unlocked position.

Figure 4 is a similar view showing the covering piece in the closed and locked position.

Figures 5 and 6 show respectively the supporting and anchoring bracket and the 95 movable covering piece unassembled.

Figure 7 is a reduced plan or rod support in open position showing rod ready to be inserted into the position indicated by dotted lines.

Figure 8 is a similar plan to Figure 7 showing the rod support in the closed and locked position.

Figure 9 is a front elevation of Figure 7. The supporting and anchoring bracket A 105 consists of an anchor plate 20 adapted to be secured in position by screws 21, a vertically disposed right-angled projecting

member 22, on the outer end of which are top and bottom vertical extensions forming hinge or trunnion pins 23; and a horizontally disposed right-angled projecting member 24, with a vertically projecting lug or catch member 25 extending from its front edge.

The movable covering piece B which is preferably rectangular in form has D shaped apertures 26 in its two horizontally disposed sides 27 and 28. The trunnion pins 23 of bracket A are placed into these apertures which are of such a size as to permit of the free movement of the covering piece B on 10 and about the same. A slot or locking device 29 is formed in the top side 27, of covering piece B and is adapted to embrace and engage the complementary catch 25 on bracket A, when the covering piece B is 15 swung into the closed position as shown in Figure 4.

The end of the rod C rests on the lower horizontal side 28 of covering piece B and abuts against the projecting member 22 of bracket A. To close and lock the supporting bracket, the covering piece B is lifted vertically and swung round until it is in the position shown in Figure 3 it is then 20 dropped or pressed into the position shown in Figure 4 when the locking device 29 on covering piece B engages the catch device 25 on bracket A. The top edge of catch device 25 may be slightly inclined to facilitate the locking movement. To release the rod the 25 covering piece B is lifted from the position shown in Figure 4 to that shown in Figure 3 and swung outwards into the position shown in Figure 1.

Referring now to Figures 10 to 19. 40 Figure 10 is a perspective view of a slight modification in the construction of supporting and anchoring bracket A. The horizontally disposed projecting member 24 as shown in Figure 5 is dispensed with and the 45 catch device 25 is formed on a vertically disposed arm 22^a projecting from the anchor plate 20. The covering and locking piece B is as hereinbefore described with reference to Figures 1 to 9. Figure 11 is a 50 perspective view of a similar modification to that shown in Figure 10 with the supporting bracket A extended outwards, and the consequent slight modification of the anchoring plate 20.

55 Figure 12 is a similar view to Figure 11 showing the covering piece B in the closed and locked position.

Figure 13 is a perspective view of a modification similar to that shown in Figure 10 60 with the anchor plate 20 vertically extended and bent at right angles to permit of the bracket being secured to the under face of a shelf or the like.

Figure 14 is a perspective view showing a 65 further modification in the construction of

the bracket A. In this case two vertically disposed and parallel arms 22^b and 22^c project from the anchor plate 20. This modification is devised to permit of the rod being supported independently of the covering 70 piece B in cases where the supported rod carries heavy curtains or other additional weight.

Figure 15 is a perspective view showing a further slight modification in the construction 75 of the bracket A as shown in Figure 5. In this case a second horizontally disposed member 24^a projects from the bottom edge of anchor plate 20 which is also slightly modified in design. This modification has 80 the same function as the modification shown in Figure 14.

Figure 16 is a perspective showing a modified construction of the locking device, otherwise the supporting bracket shown in this 85 Figure is similar to that illustrated in Figure 1. In this case the catch device on bracket A consists of a vertical extension 25^a and the locking device consists of a D shaped aperture 29^a in top side 27 of covering piece B. 90

Figures 17 and 18 are two perspective views from different angles showing an alternative method of supporting the covering and locking piece B on the bracket A. In this case the top hinge pin 23^a is formed on 95 the covering piece B and takes into a D shaped aperture 26^a in a horizontally disposed projecting lug 22^d on bracket A.

The lower hinge pin 23 is on bracket A and takes into aperture 26 in covering piece 100 B in the manner hereinbefore described and as illustrated in all the other figures of the drawings.

Figure 19 is a perspective view showing a 105 modification in the construction of the device as shown in Figure 14. In this case the catch device 25 which consists of a turned down lug is on the covering piece B and the locking device 29 which consists of a hook on the free end of projecting arm 22^b is 110 on the bracket A. This modification is also illustrated in Figures 17 and 18.

The operation hereinbefore described to move the covering piece B from the closed and locked position on bracket A to the free 115 and open position thereon, and vice-versa, and as illustrated in Figures 1, 3 and 4 equally applies to all the modifications herein described with reference to Figures 10 to 19. 120

I claim:

1. A supporting and holding device for rods comprising a right angled bracket provided with means to facilitate its attachment to a wall, a substantially U-shaped member pivotally connected to said bracket and capable of movement axially of the pivot, and cooperating locking elements provided on the member and said bracket and capable of being brought into engagement 130

only by a combined swinging and axial movement of said member, for holding the member in a predetermined position.

2. A supporting and holding device for rods comprising a bracket provided with means to facilitate its attachment to a wall, a rod holding member pivotally connected to said bracket and capable of movement axially of the pivot, and cooperating locking elements provided on the member and said bracket and capable of being brought into engagement only by a combined swinging and axial movement of said member, for holding the member in a predetermined position.

3. A supporting and holding device of the kind defined by claim 2 in which the bracket includes an anchor plate provided with an angular extension provided with integral lugs forming the pivot pintles of the means for pivotally connecting the member to the bracket.

4. A supporting and holding device of the kind defined by claim 2 in which the bracket consists of a substantially U-shaped member, one leg of which carries the pintles of the means for pivotally connecting the member to the bracket, and the other leg of which carries a part of the elements for locking the member in a predetermined position relatively to the bracket.

5. A supporting and holding device of the kind defined by claim 2 in which the holding member is of substantially U-shaped construction and is provided with aligned D-shaped slots forming a portion of the elements for pivotally connecting the holding member to the bracket.

6. A supporting and holding device of the kind defined by claim 2 in which the locking elements include an integral lug provided on the bracket and a recess provided on the holding member and designed to cooperate with said lug.

7. A supporting and holding device of the kind defined by claim 2 in which the locking elements consists of an integral lug provided on the bracket and having an inclined surface, and a recess provided in the holding member and designed to cooperate with said lug.

8. A supporting and holding device for

rods comprising a substantially U-shaped bracket, the crosshead of which is furnished with apertures to receive screws for attaching the bracket to a wall, one of the legs of the substantially U-shaped bracket being provided with oppositely extending pivot pintles and the other leg having a projecting lug, and a substantially U-shaped holding member provided with aligned slots engaging said pintles, said holding member also having a recess designed to cooperate with the lug for locking the holding member in a predetermined position relatively to the bracket.

9. A supporting and holding device for rods comprising a sheet metal right angled bracket provided with means to facilitate its attachment to a wall and having an integral hinge pintle, a locking lug integral with said bracket, a substantially U-shaped member having a slot engaged by said pintle and capable of axial movement along the pintle, said member having a surface adapted to engage said lug when the member is swung and moved axially to bring the cross-head of said U-shaped member into parallel relation with the wall to which the bracket is attached.

10. A supporting and holding device for rods comprising a sheet metal bracket member including a base adapted to be connected to a wall, an arm integral with said base and arranged at right angles thereto, a lug integral with said base, and a substantially U-shaped sheet metal member, one of said members being provided with an integral hinge pintle and the other member being provided with a slot through which the pintle passes, said substantially U-shaped member being capable of axial movement, and a surface provided on said U-shaped member and adapted to engage said lug when the U-shaped member is swung and moved axially to bring the cross-head of the U-shaped member into a plane parallel to the base of said bracket member.

In testimony whereof he has affixed his signature in presence of two witnesses.

JOSEPH BENJAMIN ALLEN.
